UNITED STATES PATENT OFFICE

WILLIAM WESTON, OF INDEPENDENCE, MISSOURI, ASSIGNOR TO J. F. PRITCHARD & CO., OF KANSAS CITY, MISSOURI, A CORPORATION OF MISSOURI

COOLING TOWER

Application filed December 5, 1927. Serial No. 237,757.

My invention relates to cooling towers, and more particularly to decks of cooling towers, the principal objects of the invention being to divide the falling water frequently into a multiplicity of small drop-curtains formed of separated drops, to maintain the spacing of slot-forming elements, to minimize warping, splitting and other distortion of deck members, to provide for the interception of substantially all drops falling through the tower, and to facilitate the handling of deck members and the erection of cooling towers.

In accomplishing these and other objects of the invention I have provided improved details of structure, the preferred forms of which are illustrated in the accompanying drawings, wherein:

Fig. 1 is a perspective view of a portion of a cooling tower.

Fig. 2 is a detail perspective view of a section of a deck, one deck member being shown in separated position.

Fig. 3 is a detail enlarged perspective fragmentary view of a deck member from beneath the same, showing the taper terminal walls of longitudinal slots.

Fig. 4 is a vertical section of a deck member on the line 4—4, Fig. 2.

Referring in detail to the drawings:

1 designates posts, 2 ties, 3 supporting struts, and 4 louvers of a cooling tower of ordinary construction. My invention relates particularly to similar trays or decks 5, each consisting of a plurality of deck members comprising slats or strips 6 preferably of wood, several deck members being assembled and joined by battens 7 to constitute a section of a deck. The sections are disposed so that the slats lie longitudinally of the tower on the struts between the posts and are provided to intercept water falling through the tower from a supply source not shown.

There are a plurality of similar decks and one only will be described. The slats 6 are arranged in spaced relation on the struts, providing the longitudinal channels 8 formed by vertical walls 9 and 10 of adjacent slats. In the ordinary structure of a

cooling tower, the slats are relatively thick and narrow, and the falling water falls through the channels or trickles down the walls of slats to fall to the deck below or to a receiver not shown. I provide slats of special form and structure, and particularly slats relatively wide and thin, and provided with longitudinal slots such as 11. The slots are preferably aligned to constitute a series or line of slots spaced by tenons 12 and I also preferably provide a plurality of similar slots 13 and 14 parallel with the slots 11 and in staggered relation therewith. The plurality of separated slots so provided, which tend to break up the falling water streams, is particularly practicable by reason of the thinness of the members, and their relative wideness.

A further feature of the deck members contributing to the distribution of water in desired extended sheets and maximum extension, consists in tapering the end walls of the slots as indicated by 16 so that the length of a slot on the upper surface of a deck member is less than the length of the slot on the lower surface. Water tends to move along the end walls of the slots, and falling from the lower edges of the elongated lower slot opening, provides a water-drop curtain falling in longer sheets than is represented by the length of the slots in the upper surface of the members. Deck members having slots provided with the taper end walls are, therefore, preferably laid with the longer openings of the slots directed downward.

The tenons of deck members constructed as described have differential length on the upper and the lower surfaces of the deck members, the relatively short tenon surface such as designated 17 in relation to the slot end walls suggesting the differentiation. The tapering of the slots therefore provides sufficient spacing of the slots, and sufficient length of tenons, considering the upper face of the members, to secure desired strength and stiffness, a result to which the staggering of the slots contributes, and at the same time provides for delivery of water drops in substantially continuous vertical planes. The lateral staggering of the slats and slots in

vertically adjacent decks adds to the distributor effect.

Deck members having been provided as described, and assembled in decks of a cooling tower, water delivered to a deck is distributed through the slots in a number of curtains or streams of drops in position to be cooled by the air currents, the structure providing for a substantial increase in the water surface presented to the air currents and therefore an increase in cooling efficiency.

In a deck constructed in this manner, the relative rigidity of the wider strips provides accurate spacing of strips when installed, and the accurate spacing, in connection with the original provision of slots, provides for more efficient distribution of water upon original installation. Further, the structure will retain the characteristic of efficiency, since the wider strips, being stiffer, tend to preserve the original spacing of the strips; which, with the slotted construction, provides for a minimum possibility of splitting and warping to distort adjacent vertical walls to a prejudicial degree. The reduction of the warping hazard permits construction of the deck members from thinner material, reducing cost of material; and the use of thinner material, combined with the provision of the slots, permits forming of relatively wide strips, thereby minimizing the labor of handling and assembling. The staggering of slots provides the tenons which constitute a transverse stiffening element, whereby a substantial increase in lateral strength is attained, substantially proportionate to the differentiate in width of the members over the width of ordinary deck slats. A larger variety of relations between slots of a deck, and between slots of vertically adjacent decks, is possible with the illustrated structure, so that the maximum number of drops of water can be intercepted, a minimum number will fall directly through the slots, and a maximum degree of spraying effect will be produced.

What I claim and desire to secure by Letters Patent is:

1. In a cooling tower, a deck including parallel slats spaced laterally to form channels between adjacent slats, each slat having a plurality of slots extending longitudinally therein, each slot having end walls diverging to form a longer opening on one side of the slat than on the other, the slats being positioned on the support to present the sides thereof having the longer openings downwardly.

2. In a cooling tower, a deck including a slat having a plurality of parallel series of aligned slots, each slot having end walls diverging to reduce the spacing between aligned slots on one side of the slat, and the slat being positioned with the side thereof having the reduced spacing of aligned slots presented downwardly.

3. In a cooling tower of the type described, a tray having a plurality of rows of slots arranged staggeredly, each slot being longer on the under side of the tray than on the top side.

In testimony whereof I affix my signature.

WILLIAM WESTON.
